UNITED STATES PATENT OFFICE.

ADOLPH WESTMEYER, OF PACIFIC, MISSOURI.

DESIGN FOR A WIRE-STRETCHER SHANK.

SPECIFICATION forming part of Design No. 21,592, dated May 31, 1892.

Application filed August 8, 1891. Serial No. 402,180. Term of patent 7 years.

To all whom it may concern:

Be it known that I, ADOLPH WESTMEYER, a citizen of the United States, residing at Pacific, in the county of Franklin and State of Missouri, have invented and produced a new and original Design for Wire - Stretcher Shanks, of which the following is a specification, reference being had to the accompanying drawings, in which—

10 Figure 1 is a perspective view, and Fig. 2 is an edge view, of a wire-stretcher shank, showing my design.

At one end of the shank is produced a claw-like representation C, the central lines C' of 15 which converge inwardly, producing a V-shaped effect, while its outer lines merge into

the lines of the shank at C², as shown. The lines of the shank are parallel from C² to a point C³, where they flare outward and then inward, from which point the shank is flattened, its lower line extending straight forward to its extremity C⁴, while the lines of its upper side produce a step-like effect at C⁵.

At C⁶ C⁶ the lines of the shank converge from C⁴ to the extremity C⁵, as shown in Fig. 1. 25

I claim—

The design for a wire-stretcher shank herein shown and described.

ADOLPH WESTMEYER.
